ABSTRACT OF THE DISCLOSURE

New explosive and/or pyrotechnic complexes are formed from ferrocene and its derivatives with specified inorganic nitrates, i.e., mercuric, ceric, and cupric, each of these nitrates known generally as being insensitive to sparks or impact.

The invention described herein may be manufactured, used and licensed by or for the Government for governmental purposes therein without the payment to us of any royalties thereon.

This invention relates to explosives and pyrotechnic materials and more particularly concerns ferrocene and its derivatives to form explosive and/or pyrotechnic complexes with selected inorganic nitrates.

Commonly used prior art primary explosives leave something to be desired. For example, as an explosive ingredient, ammonium nitrate is extremely hygroscopic. Mercury fulminate as an ingredient in priming compositions is undesirably sensitive to light and elevated temperatures. Small quantities of mercury are formed which produce amalgams with copper, brass, and bronze, leading to metal failure. Lead styphnate, which has replaced mercury fulminate as an ingredient in detonators and primary compositions, is a relatively poor initiator when compared with other primary explosives. Other primary explosives suffer drawbacks which prevent their utility from being completely acceptable for military applications.

and pyrotechnic complexes from ferrocene and its derivatives with specified nitrates, the complexes having a wide range of controllable characteristics.

Other and further objects of the invention will become apparent as the invention is further described hereinafter.

In accordance with the above objects, explosive or otherwise energetic complexes are formed from ferrocene and its derivatives on the one hand and mercuric, ceric, and cupric nitrates on the other. The structure of the ferrocene reactant (bis-cyclopentadienyliron) has been reported in the literature by Wilkinson et al., "Journal of the American Chemical Society," vol. 74, page 2125 (1952), and may be described as a sandwich-type structure having an iron atom between two staggered cyclopentadiene rings as shown below:

20

25 Some of our complexes are primary explosives and are useful in igniting charges and detonators, and as ingredients in priming compositions and pyrotechnic mixtures. The complexes will be prepared thus:

30 A solution of ferrocene or ferrocene derivative in a solvent such as benzene, methyl or ethyl alcohol, or ether is slowly added, with stirring, to a filtered solution of the inorganic nitrate (drying unnecessary) dissolved in excess in methyl alcohol, at room temperature, usually causing precipitation of the complex. The product is collected on a filter under suction, without delay, and washed with small quantities of methyl alcohol and benzene in succession, then air-dried. In some cases, solvents such as ethyl or isopropyl alcohols, acetone, or tetrahydrofuran may be substituted for methyl alcohol.

35 40 The following table lists complexes prepared by the above method:

TABLE I.—EXPLOSIVE COMPLEXES OF FERROCENE AND ITS DERIVATIVES

No.	Complex	Color	Sensitivity		
			Impact ^a	Spark ^b	Heat ^c
1.	FeH ₄ ·xHg(NO ₃) ₂	Blue	E ^f	+ ^g	+
2.	FeBr ₄ ·xHg(NO ₃) ₂	Light-brown	E	+	+
3.	FeCN·xHg(NO ₃) ₂	Yellow-tan	E	+	+
4.	FeC ₄ H ₉ ·xHg(NO ₃) ₂	Yellow-green	E	+	+
5.	Fe ₂ Hg ₂ ·xHg(NO ₃) ₂	Blue-green	E	+	+
6.	Fe ₃ P·xHg(NO ₃) ₂	Yellow-tan	E	+	+
7.	Fe ₃ PC ₆ H ₅ ·xHg(NO ₃) ₂	Light-brown	E	+	+
8.	Fe ₃ P(C ₆ H ₅) ₂ ·xHg(NO ₃) ₂	Light-yellow	+	+	+
9.	Fe ₃ PO·xHg(NO ₃) ₂	Tan	E	+	+
10.	Fe ₃ PS·xHg(NO ₃) ₂	Light-tan	E	+	+
11.	Fe ₃ Se·xHg(NO ₃) ₂	Yellow-tan	E	+	+
12.	(Fe ₃ PN) ₂ C ₆ H ₅ ·xHg(NO ₃) ₂	do	+	+	+
13.	Fe ₂ P(O)N(C ₆ H ₅) ₂ ·xHg(NO ₃) ₂	Light-brown	E	+	+
14.	Fe ₂ P(O)OH·xHg(NO ₃) ₂	Blue	E	— ^h	+
15.	FePh(O)OH·xHg(NO ₃) ₂	Light-blue	E	+	+
16.	FeSi(C ₆ H ₅) ₂ OH·xHg(NO ₃) ₂	Blue-black	+	+	+
17.	Fe ₂ Si(C ₆ H ₅) ₂ ·xHg(NO ₃) ₂	Light-blue	+	+	—
18.	FeAS(C ₆ H ₅) ₂ ·xHg(NO ₃) ₂	Bright-yellow	+	+	+
19.	FeH ₂ ·xCe(N ₃) ₄	Dark-blue	+	+	+
20.	Fe ₃ P·xCe(N ₃) ₄	Blue	E	+	+
21.	Fe ₃ PO·xCe(N ₃) ₄	Blue-black	E	+	+
22.	Fe ₃ PO·xCu(NO ₃) ₂	Dark-green	+	+	+
23.	Fe ₃ P·xHgNO ₃	Yellow-orange	+	+	+
24.	Fe ₃ PO·xHgNO ₃	do	+	+	+

^a Hammer-blow applied. ^b Tesla coil used. ^c Complex contacted with hot plate.
^d FeH = Ferrocene. ^e Fe = Ferrocenyl = C₅H₅FeC₅H₄—. ^f E = Explodes. ^g = Sensitive. ^h = Ininsensitive.

It is therefore an object of this invention to provide improved explosive and pyrotechnic complexes which minimize the disadvantages aforesubdiscussed.

Another object of the invention is to provide explosive and pyrotechnic complexes from specified inorganic nitrates known in the art to be generally inert.

Still another object of the invention is to form explosive

70 An explosive complex (Item No. 6, for example) is obtained from Hg(NO₃)₂ and Fe₃P upon adding a benzene solution of the latter to a methyl alcohol solution of the former, employing the reactants in a range of molar ratios of about 3 to 1 up to about 20 to 1. For the compounds listed in Table I, the ratios will vary from between about 1 to 1 to about 20 to 1.

The mercuric nitrate and Fe_3P in a 1:1 molar ratio gave a product which could be ignited with a spark, but could not be detonated by impact with a hammer. With a 2:1 molar ratio, a mixture of spark ignitable product and hammer explodable product was obtained. When the ratio was increased to 3:1, the product obtained was readily exploded. With ratios greater than 3:1, higher yields of the explosive product were possible.

In the practice of our invention, the weight of $\text{Hg}(\text{NO}_3)_2$ will be at least 10 times greater than that of the ferrocene derivative, yielding the complexes substantially quantitatively. In the case of Fe_3P and $\text{Hg}(\text{NO}_3)_2$, the molar ratio will be about 18 to 1, the $\text{Hg}(\text{NO}_3)_2$ being in excess. The excess $\text{Hg}(\text{NO}_3)_2$ after precipitation of the complex, may be used in forming more complex from additional ferrocene derivative.

EXAMPLE I

A benzene solution containing 12 g. Fe_3P was slowly added, with stirring at room temperature to a solution containing 120 g. $\text{Hg}(\text{NO}_3)_2$ prepared by dissolving the nitrate in excess methyl alcohol and filtering off the insoluble solids. 31.5 g. of complex precipitated. After being washed with methyl alcohol and benzene in succession, a small sample was dried 1 hour at 100° C. in vacuo which produced in 6.7% weight loss. Based on a quantitative precipitation of all the Fe_3P , the apparent molar ratio of $\text{Hg}(\text{NO}_3)_2$ to ferrocene derivative in the complex was 4.5.

EXAMPLE II

The procedure set forth under Ex. I was used, the compounds of Table I, Item No. 9, yielding:

EXAMPLE III

The procedure set forth under Ex. I was used, the compounds of Table I, Item No. 3 yielding:

In the latter two examples above, when the weight of the $\text{Hg}(\text{NO}_3)_2$ was 10 times the weight of the ferrocene derivative, the molar ratio of the reactants employed was

and

With alkyl or aryl substituted ferrocenes, addition of ether or benzene was necessary to cause the complexes to separate from solution.

Ceric ammonium nitrate was used as the source of ceric nitrate in the complexes shown in Table I. It would seem that the complexes contain no ammonium since NH_4NO_3 itself yields no complex.

Complexes of mercurous nitrate with Fe_3P and Fe_3PO were found to be impact, spark, and heat sensitive, but without explosion capability under a hammer blow, contrary to behavior when mercuric nitrate was used. Complexes prepared from triphenylphosphine and mercuric or mercurous nitrates were completely inactive even though mercurous nitrate itself is known to explode when heated to boiling. It is apparent therefore that complexing of the inorganic nitrate to a ferrocene species is essential and

that the activity exhibited by the complexes cannot be attributed to mercurous nitrate per se. Thus, in the case of complexes with mercuric nitrate, activity cannot be attributed to reduction of mercuric to mercurous. (The blue color of some of the complexes tabulated in Table I may be due to oxidation of ferrocene to ferrocinium

10 and tend to indicate reduction of mercuric to mercurous.) Substitution of ceric for mercuric further substantiates the above. Mercurous nitrate is not sensitive to impact with a hammer, nor is it spark sensitive. Physical mixture of mercurous or mercuric nitrate with ferrocene derivatives 15 are not active.

The product obtained from $\text{Cu}(\text{NO}_3)_2$ and Fc_3PO gives a pyrotechnic display consisting of rapid sparking when contacted with a hot plate. With cobalt and ceric nitrates, a weak flash is observed, while mercuric nitrate yields quick, bright flashes. When compared to Fc_3PO , bromoferrocene and diferrocylnitro are superior flash characteristics, i.e. brighter flames. Such materials may find use as ingredients in pyrotechnic compositions and as secondary explosive ingredients. Except for ammonium nitrate, inorganic nitrates per se do not flash on a hot plate. Ammonia nitrate, however, requires a much higher temperature than do our complexed nitrates before flashing occurs.

Item No. 16, complex $\text{FeSi}(\text{C}_6\text{H}_5)_2\text{OH} \cdot x\text{Hg}(\text{NO}_3)_2$ 30 first precipitates as a red solid on forming, then becomes a blue-black taffy. In the latter form, the substance is useful as a single-ingredient fuse that can be applied with a brush. Upon standing, the taffy-like material appears to undergo polymerization to a brittle glass, and may find 35 use in high-energy materials that have been cast or molded.

We claim:

1. A new composition of matter comprising an explosive pyrotechnic complex formed by ferrocene and derivatives of ferrocene with an inorganic nitrate selected from the group consisting of mercuric nitrate, mercurous nitrate, ceric nitrate, and cupric nitrate.
2. The composition of claim 1 wherein said complex is ferrocene $\cdot x\text{Hg}(\text{NO}_3)_2$.
3. The composition of claim 1 wherein said complex is bromoferrocene $\cdot x\text{Hg}(\text{NO}_3)_2$.
4. The composition of claim 1 wherein said complex is cyanoferrocene $\cdot x\text{Hg}(\text{NO}_3)_2$.
5. The composition of claim 1 wherein said complex is butylferrocene $\cdot x\text{Hg}(\text{NO}_3)_2$.
6. The composition of claim 1 wherein said complex is diferrocylnitro $\cdot x\text{Hg}(\text{NO}_3)_2$.
7. The composition of claim 1 wherein said complex is triferrocylnitro $\cdot x\text{Hg}(\text{NO}_3)_2$.
8. The composition of claim 1 wherein said complex is diferrocylnitrophenylphosphine $\cdot x\text{Hg}(\text{NO}_3)_2$.
9. The composition of claim 1 wherein said complex is ferrocenylphenylphosphine $\cdot x\text{Hg}(\text{NO}_3)_2$.
10. The composition of claim 1 wherein said complex is triferrocylnitrophenylphosphine $\cdot x\text{Hg}(\text{NO}_3)_2$.
11. The composition of claim 1 wherein said complex is triferrocylnitrophenylsulfide $\cdot x\text{Hg}(\text{NO}_3)_2$.
12. The composition of claim 1 wherein said complex is triferrocylnitrophenylselenide $\cdot x\text{Hg}(\text{NO}_3)_2$.
13. The composition of claim 1 wherein said complex is benzene-1,4-bis(triferrocylnitrophenylphosphineimine) $\cdot x\text{Hg}(\text{NO}_3)_2$.
14. The composition of claim 1 wherein said complex is diferrocylnitrophenylphosphinic amide $\cdot x\text{Hg}(\text{NO}_3)_2$.
15. The composition of claim 1 wherein said complex is diferrocylnitrophenylphosphinic acid $\cdot x\text{Hg}(\text{NO}_3)_2$.
16. The composition of claim 1 wherein said complex is ferrocenylphosphinic acid $\cdot x\text{Hg}(\text{NO}_3)_2$.
17. The composition of claim 1 wherein said complex is ferrocenylidphenylsilanol $\cdot x\text{Hg}(\text{NO}_3)_2$.

18. The composition of claim 1 wherein said complex is diferrocyldiphenylsilane· x Hg(NO₃)₂.

19. The composition of claim 1 wherein said complex is ferrocenyldiphenylarsine· x Hg(NO₃)₂.

20. The composition of claim 1 wherein said complex is ferrocene· x Ce(NO₃)₄.

21. The composition of claim 1 wherein said complex is triferrocyenylphosphine· x Ce(NO₃)₄.

22. The composition of claim 1 wherein said complex is triferrocyenylphosphine oxide· x Ce(NO₃)₄.

23. The composition of claim 1 wherein said complex is triferrocyenylphosphine oxide· x Cu(NO₃)₂.

24. The composition of claim 1 wherein said complex is triferrocyenylphosphine· x HgNO₃.

25. The composition of claim 1 wherein said complex is triferrocyenylphosphine oxide· x HgNO₃.
